RAILWAY CROSSING SIGNAL

Frank H. Richterkessing, Louisville, Ky., assignor
to Nachod & United States Signal Co., Inc.,
Louisville, Ky., a corporation of New York

Application January 20, 1932, Serial No. 587,686

15 Claims. (Cl. 246—128)

My invention relates to improvements in railway signaling systems, especially those adapted for use in connection with warning devices installed at the intersection of a highway and an electric railway line; hence, I have illustrated in the accompanying drawings the application of my invention to electric signal apparatus for use on railways, in which the moving train is adapted to automatically close the electric control circuit 5 or circuits through the axle and wheels thereof for the purpose of controlling the actuation of the electric bell and visual signals.

The main object of my invention is to protect a crossing or other danger point on the railway 10 by ringing a bell or giving an alarm, which is augmented by a visual indication consisting of alternately flashing red lights, all of which shall occur when the train approaches within a certain distance of the highway and shall continue until 15 the entire train has cleared the highway or danger point.

A still further object of my invention is to provide a method for discontinuing the audible signal after a predetermined lapse of time, in the 20 event the train has not cleared the highway. The system is further so arranged that the visual indication shall continue to operate when the latter takes place and until the train actually clears the highway.

30 A still further object of my invention is to provide a normal indication at the highway which will normally burn and indicate the location of the signaling apparatus. It is further intended that the normal indication be arranged so as to 35 flood light the signaling apparatus.

A still further object of my invention is to provide signal indications which may be observed by the operator of the railway train, and which will indicate the proper operation of the signaling and control apparatus upon the approach of 40 a train to the highway.

A still further object of my invention is to arrange the latter mentioned indications so that 45 they will be displayed only while the audible indication exists at the highway.

A still further desired result obtained by my 50 invention is the automatic re-establishing of the audible signal at the highway and the signal indications to the train, when a second train (or a first train as may be the case in switching movements) approaches the intersection and operates past the normal starting point.

A still further desired result effected by my 55 invention is its application to locations where the

conventional type of continuous rail circuit signaling exists.

A still further desired result effected by my invention is the controlling of the apparatus connected to the rail circuits by a very low voltage and the other control apparatus involving line wire control being operated on a higher voltage.

A still further desired result obtained in my invention is the embodiment of a track control which will cause the display of the highway indications when the approach or clearing sections become short circuited.

My invention further consists of certain novel functions and characteristic constructions as fully disclosed in the following description, and 15 accompanying drawings in illustration thereof, in which:

Figure 1 is a diagrammatic representation of my invention indicating the control as being located within a block signaling system utilizing 20 the conventional continuous rail control circuits.

Figure 2 is a modified diagrammatic representation of my invention as disclosed in Figure 1 being further arranged so that the visual highway signals will be discontinued when the audible signal is discontinued. The control apparatus of Fig. 2 is indicated as being within a railway system which does not utilize running rails 25 for other signaling.

Figure 3 illustrates a modified manner of connecting the clearing control circuit to the insulated sections.

Figure 4 is a detail of my invention showing the specific manner in which the wheels and 35 axles of the train cooperate to control the novel clearing circuit set forth in my invention.

With further reference to Figure 1, the characters RR and RR! designate the running rails of a railway system. At each extremity of the running rails the conventional symbol is employed to illustrate an impedance bond represented by the characters IB. These devices are not necessary in the operation of my invention but are necessary in the operation of the block signaling system, utilizing the well known principle of continuous rail circuits, when the rails are employed as conductors for the return propulsion current of the vehicles operating thereon. At one extremity of the rail section the characters TB indicate the track transformer which is employed to supply the track voltage through connecting wires 56 and 57 for the operation of the block signal system. At the other extremity the characters BR represent the track relay which is connected to the rails through 50 55

wires 58 and 59 and energized from the latter mentioned transformer to control the block signal represented by the characters BS. In the drawings, characters BX and CX represent the 5 respective poles of a 110 volt alternating current circuit. It will be further noted that the armature ABR of the track relay BR is normally in contact engagement with its front contact 73 thereby normally holding the block signal BS in 10 a clear position as indicated, the circuit being completed from BX through wire 61, armature ABR of relay BR, front contact 73 of relay BR, wire 62, block signal BS, through wire 60 to the other power terminal CX. It is believed that a 15 further description of the parts embracing the block signaling system is not necessary, since the applicant wishes to show how his system may be employed within such a system and not affect the operation of same.

20 With further reference to Figure 1 it will be noted that the running rail RR1 is provided with several short insulated rail sections illustrated by characters X, X1, X2, X3, X4, and X5. Each of the latter mentioned short rail sections is 25 employed in the control of the applicant's invention and will be further treated in detail with the description of the control embracing each respective section. The short rail sections indicated by the characters X and X1 respectively 30 are employed to control the track relays E and F, which in turn are employed to control the starting of the signal indications at the highway when a train engages the insulated rail sections X and X1 respectively upon approaching 35 the intersection, and which are further employed to prevent the signal indications at the highway from being started by a train engaging the insulated rail sections X1 and X respectively upon leaving the highway. The circuits of the track 40 relays E1 and F1 cooperate with the short insulated rail sections X4 and X5 to produce the same result as outlined for relays E and F.

45 At the highway the character B illustrates an audible warning signal which may be a vibrating bell, polarized bell or siren. The characters FL and FL2 designate the alternate flashing red lights which are actuated while a train approaches and clears the highway. The character Y illustrates the normally burning marker light 50 which is employed to provide a normal burning yellow indication and the flood lighting of the signal standard. This indication is burning only when the train is not approaching the highway and is dark when either the audible signal or 55 flashing light signals are given. The characters FR designate a relay for controlling the alternate energization of the red signal lamps FL and FL2 respectively. This relay, operating on alternating current, is controlled by a small induction motor symbolically represented by CFR and D respectively. The element D of the induction motor may be a disk or drum as is ordinarily employed in small conventional induction motors, and which, through suitable gearing drives 60 the cam CAM. The latter mentioned cam in revolving alternately engages the contact arms AFR and AFR1 respectively in such a manner that the contact arms are permitted to alternately engage contacts 23 and 24 respectively. 65 The characters SR designate a slow release relay which is employed to give the audible indication for a predetermined time interval while a train approaches the highway. This relay is instantaneous in pick up and is retarded in release 70 through the employment of some well known 75

retarding principle, such as a motor driven device or an oil dash pot arrangement. The latter mentioned retarded release feature is symbolically represented by the characters CS. The character L designates a novel form of latching or locking relay employed in my invention and embraces each of the operating coils CL1 and CL2 respectively. The two operating coils CL1 and CL2 are displaced with a definite relation to each other, and in such a manner that they 10 will operate a mechanical locking device LO disposed therebetween. When the operating coil CL1 is energized, and raises its armature A1, the armature will be mechanically held in the raised position by the locking arm LO, and when the operating coil CL2 is energized and raises its respective armatures A2 and AL2 the locking arm LO will be moved out of locking engagement with the armature A1. It is believed that a further detailed discussion of this operation is not necessary since it will be obvious to those skilled in the art, how such a relay might be constructed to perform in the manner designated. The characters T2 symbolically represent the track transformer employed for giving the reduced 20 voltage for the control of the clearing coil CL2 which is connected through wires 40 and 38 to the short insulated rail sections X2 and X3 respectively. 25

30 In each of the drawings accompanying the specification like numerals and characters have been employed to designate identical or similar parts. It is therefore believed that a lengthy description of each of the figures is not required since the teachings of one description may be 35 applied to the remaining figures.

35 Each of the relays illustrated in Figure 1 is shown in its normal operating condition, and it is believed that a discussion relating to the normal circuits will give general information relative to the control apparatus. As was heretofore mentioned the signal standard at the highway is provided with a normally burning indication and floodlighting of the signal standard. The circuit for the normal display of the indication 40 is completed from the BX terminal of the power source, through wire 6, wire 9, armature A1 of locking relay L, back contact 27, wire 28, back contact 29, through the armature AL2 of relay L, wire 30, signal lamp Y, wire 14, wire 11 to the 45 other terminal of the power source CX. From the latter it will be noted that either of the armatures A1 or AL2 raised out of contact engagement with either of their respective back contacts 27 or 29 will open the circuit to the normal burning indication Y. 50

55 A train approaching the highway and operating over the short insulated sections X and X1 will operate relays E and F which in turn will control the starting of the highway signal indications. When the first wheels of the train engage the short section X a circuit will be completed from the secondary S of transformer T through wire 51 to the running rail RR1, through the wheels and axle of the train, to the short rail 60 section X, through wire 50, armature AE of relay E, back contact 55, wire 54, operating coil CF of relay F, wire 53, to the other secondary terminal of the transformer T. The energization of the operating coil CF will raise the contact arm 65 AF into contact engagement with its front contact 44, thereby completing the circuit for the control of relays SR and L respectively. The latter mentioned circuit is completed from the BX power terminal, through wire 6, wire 9, wire 70 75

10, operating coil CL1 of relay L, wire 41, operating coil CSR of relay SR, wire 42, wire 43, front contact 44 of relay F, armature AF, through wire 3, to the other power terminal CX. The completing 5 of this circuit will cause the armatures of relays SR and L to be raised into contact engagement with their respective front contacts. Incident to the engagement of the armature A1 with its front contact 14, the locking lever LO 10 will mechanically retain the armature A1 in its raised position as was heretofore described. With the armatures ASR and A1 in contact engagement with their respective front contacts, circuits will be established for giving the combined audible and visual signals at the highway, and the signal indications M and M1 to indicate to the train operator that the signals have been properly operated. It will be noted that a circuit is completed from the BX power terminal through wire 20, wire 9, armature A1, front contact 14, wire 20, wire 22, operating coil CFR of the motor driven relay FR, wire 13, wire 11, to the other power terminal CX. The energization of the operating coil CFR will result in the disk or drum D 25 of the relay FR revolving, which in turn will operate the cam as heretofore described, to permit the contact arms AFR and AFR1 to alternately engage their respective contacts 24 and 23. With the contact arm AFR in engagement 30 with its contact 23 a circuit will be established for the energization of signal lamp FL2, the latter circuit being completed from the BX power terminal, through wire 6, wire 9, armature A1 of relay L, front contact 14, wire 20, wire 22, contact 35 23 of relay FR, armature AFR, wire 26, signal lamp FL2, wire 16, wire 15, wire 14, wire 11, to the other power terminal CX. With the disengagement of contact 23 and armature AFR, and the engagement of contact 24 and armature AFR1, the signal lamp FL2 will be de-energized and the signal lamp FL will be displayed, the circuit to the latter being completed from the feed control wire 22, through contact 24, armature AFR1, wire 25, signal lamp FL, wire 15, wire 14, wire 11 40 to the power terminal CX. As was heretofore described the relay SR is provided with a retarded release time element factor which is effective when the operating coil CSR of relay SR becomes de-energized. During this predetermined time interval, circuits will be established through the engagement of armature ASR with its front contact 21 for giving the audible signal at the highway and the signals M and M1 to the operator of the train. These circuits will be 45 established from the BX power terminal through wire 6, wire 9, armature A1 of relay L, front contact 14, wire 20, front contact 21 of relay SR, armature ASR, wire 33, wire 32, wire 31, through the control of the audible indication B, wire 17, wire 15, wire 14, wire 11, to the other power terminal CX. The wire 33 is also connected to wire 50 34 which in turn supplies current through the signal indication M, through wire 35 to the power terminal CX. It will be similarly noted that wires 33 and 32 supply current through wire 36 to the signal lamp M1 and wire 37 returns to the power terminal CX. It is obvious that the latter mentioned circuits will exist as long as the armature ASR of relay SR engages its front contact 21, or until the armature A1 of relay L disengages its front contact 14. The predetermined time interval of the relay SR is usually adjusted so that trains approaching the highway under normal speeds will clear the highway before the 55 time interval has lapsed, so that for all normal

operations the train in approaching and clearing the highway will have the full protection of the audible and visual indications.

With further reference to the circuits embracing the short insulated sections X and X1 it will be noted, that as the train advances and the front wheels disengage the short insulated section X and engage the insulated section X1 the operating coil CE of relay E will be energized and the armature AE will be raised out 10 of contact engagement with its back contact 55 thereby resulting in the operating coil CF of relay F becoming de-energized. The circuit for the energization of the operating coil E will be completed from the secondary S of transformer T through wire 51, through the running rail RR1, through the wheels and axles of the train, to the insulated section X1, wire 41, operating coil CE of relay E, wire 52, to the other secondary terminal of transformer T. It will 15 be noted that successive engagement of train wheels with the insulated section X will not re-energize the operating coil CF of relay F since its circuit will be opened at 55, but a holding circuit will be established from the short insulated section X for retaining the armature AE in the raised position. This holding circuit is completed from the secondary S of transformer T through wire 51, to the running rail RR1, through the wheels and axles of the train to the insulated section X, through wire 50, armature AE, front contact 41 of relay E, wire 48, operating coil CE 20 of relay E, wire 52 to the other secondary terminal of transformer T. It will be noted that a jumper 70 is placed about the insulated sections 25 X and X1 collectively. This jumper is not necessary for the operation of the signal system but is necessary for completing the continuous rail circuit which would have been interrupted 30 through the insertion of the short insulated rail sections. The jumper 70 is normally of such capacity so as to be useful in providing a rail equivalent for conducting the return propulsion current of the trains operating thereon. As the train approaches and crosses the highway the 35 wheels will come into contact engagement with the insulated sections X2 and X3 respectively, thereby completing the circuits for restoring the signal system to normal. It is believed that Figure 4 might be employed to more clearly illustrate 40 how the wheels and axles of the train are adapted to produce this result. Referring to Figure 4 like characters and numerals have been employed to designate the relays embracing the clearing control. The figure is further modified 45 to illustrate how the rail sections might be applied to the running rails where the rails are not employed for other signalling purposes. It will be noted that the jumpers or bond wires 77, 78 and 79 are employed to connect the running rails 50 RR and RR1 so as not to interrupt the return propulsion current flowing in the running rails. The train located on the insulated sections as 55 illustrated will complete a circuit from the secondary S2 of transformer T2, through wire 38, to the insulated section X3, through wheel W3, axle X1, wheel W2, to the running rail RR1. The running rail RR1 being electrically connected to the running rail RR through jumper 78, the circuit 60 will continue through the jumper 78 to the running rail RR, through the wheel W, axle AX, wheel W1, to the insulated rail X2, through wire 65 48, operating coil CL2 of relay L, wire 39, to the other secondary terminal of transformer T2. It will be noted that the latter described circuit was 70 75

not completed through the bearings or other metallic parts of the train other than the wheel to rail contact. It is therefore obvious to those skilled in the art that if the system was not to be operated by all trains then the wheels of certain trains could be insulated from their axles and the signal system would not be affected by the presence of such trains. It will be noted that as soon as the first car of the train effects the energization of the operating coil CL2 the armature A2 will be brought into contact engagement with its front contact 18. Again referring to Figure 1, it will be noted that as long as the armature A2 remains in contact engagement with its front contact 18, a circuit will be completed through wire 19, wires 20 and 22 which will continue the energization of the visual and audible signals of the system. This circuit will be completed from the BX power terminal through wire 6, wire 7, wire 8, armature A2 of relay L, front contact 18, wire 19, wire 20, wire 22, etc. It will be likewise noted that as long as the operating coil CL2 of relay L remains energized, the armature AL2 will be raised out of engagement with its back contact 29 thereby rendering the normal signal indication Y inoperative until the armature AL2 is restored into contact engagement with its back contact 29. It is therefore obvious to those skilled in the art that whether the train consists of a single car or a number of cars, the operating coil CL2 of relay L will remain energized until the last wheel of the train enters the highway, since successive wheels engaging the insulated sections X2 and X3 will retain the circuit embracing the operating coil CL2 energized in the manner described for Figure 4. As the train clears the highway and approaches the insulated sections X4 and X5 upon leaving the highway the front wheels of the train will engage the insulated sections X4 in advance of the section X5, energizing the operating coil CE1 of relay E1 and raising the armature AE1 out of contact engagement with its back contact and into contact engagement with its respective front contact. This operation results in the opening of the circuit including the operating coil CF1 of relay F1, and utilizes the insulated rail section X5 to provide the holding circuit as was described for relays E and F. It is obvious that relays E1 and F1 operated in this manner will not permit the armature AF1 of relay F1 to engage its front contact 46, thereby rendering the relays E1 and F1 ineffective to re-establish the signal control circuits at the highway. It is likewise obvious to those skilled in the art that a train approaching the highway and engaging the insulated section X5 in advance of the insulated section X4 will start the signal control in the same manner as was treated for relays E and F, and as the train clears the highway the signal control will be restored to normal in the same manner as heretofore treated, and further, as the train advances and engages the insulated section X1 in advance of the insulated section X the relays E and F will be rendered ineffective to reestablish the signal circuits at the highway as was treated for relays E1 and F1.

It is believed that Figure 2 accompanying the specification is self-explanatory in view of the latter description as to the exact manner in which it will operate since like numerals and characters have been employed in the figure to designate identical parts.

In Figure 2 it is intended to discontinue the audible and visual signal at the end of the pre-

determined time interval of relay SR, and therefore wire 22 connecting the relay FR for controlling the visual indications has been connected through wire 33A to armature ASR of relay SR instead of being directly connected to the front contact 21 of relay SR. The remaining circuits of Figure 2 are identical with those found in Figure 1. It will be noted, however, that the rail bonding and the installation of the insulated rail joints have been illustrated as being applied to the running rails of a system not employing the rails for other signaling purposes.

Figure 3 is intended to illustrate a modification of the manner of connecting the clearing coil CL2 of relay L to the insulated sections at the highway. In this modification it will be noted that only one insulated section is employed and that this modification introduces the feature of having the operating coil CL2 of relay L become de-energized only after the last wheel of the train clears the highway. It is believed that a further description of this modification is not necessary since it will be obvious to those skilled in the art that this result is accomplished through this modification. Likewise the teachings of the description accompanying Figure 1 can be applied to the numerals and characters employed in Figure 3.

It is obvious that further modifications and arrangements of the parts may be made from those shown and described in the above disclosure, such as the employment of track instruments to substitute for the insulated sections or other forms of circuit closing devices which will be actuated by trains passing the several locations and which it is believed will still fall within the scope of my invention.

I claim:

1. In a signaling system, a normally open circuit containing an operating coil of one relay and the armature of a second, means for closing the said circuit, a second normally open circuit containing the operating coil of the said second relay, the latter mentioned coil being adapted for attracting the said armature to interrupt the first said circuit, the said means likewise being adapted for closing the said second circuit, in combination with a circuit including an electromagnet and an armature adapted to be attracted by the first said operating coil, a circuit containing an armature adapted to be attracted by the said electromagnet, a signal controlled thereby, and another normally open circuit containing an operating coil, and other means controlled by the last mentioned coil for controlling the said signal and for restoring the said armature attracted by the said electromagnet to normal.

2. In a signaling system, a relay having a circuit, a train for closing said circuit, a second circuit, the said train closing the second circuit, and means whereby the closing of the said second circuit effects an interruption of the first said circuit, in combination with a second relay, a plurality of circuits connected with the said second relay, the first mentioned relay being adapted for closing one of the said circuits connected with the second mentioned relay and thereby effect the closure of a second circuit connected with said second relay, a signal, the closure of the latter mentioned circuit effecting the operation of the said signal, and means affected by the said train for retaining the closure of the latter mentioned circuit and restoring the said second circuit to normal.

3. In a signaling system for notifying the approach of a train, a normally open circuit containing an operating coil of one relay and the armature of a second, means for closing the said circuit, a second normally open circuit containing the operating coil of the said second relay, the latter mentioned coil being adapted for attracting the said armature to interrupt the first said circuit, in combination with a circuit including an electro-magnet and an armature adapted to be attracted by the first said operating coil, another circuit containing an armature adapted to be attracted by the said electro-magnet, a visual and an audible signal controlled by said last mentioned armature, and means associated with the circuit controlled by the armature of the first said operating coil for interrupting the said audible signal after a predetermined time.
4. In a signaling system, a normally open circuit containing an operating coil of one relay, the armature of a second and a secondary winding of a transformer, means for closing the said circuit, a second normally open circuit containing the operating coil of the said second relay and the secondary winding of the said transformer, the latter mentioned coil being adapted for attracting the said armature to interrupt the first mentioned circuit, the said means likewise being adapted for closing the said second circuit, in combination with a circuit including an electro-magnet, and an armature adapted to be attracted by the first said operating coil, a circuit containing an armature adapted to be attracted by the said electro-magnet, a signal controlled by said last mentioned armature, and another normally open circuit containing an operating coil and the secondary winding of a second transformer, the said means likewise being adapted for closing the last mentioned circuit.
5. In a signaling system, a normally open circuit containing an operating coil of one relay, the armature of a second, and a secondary winding of a transformer, means for closing the said circuit, a second normally open circuit containing the operating coil of the said second relay and the secondary winding of the said transformer, the latter mentioned coil being adapted for attracting the said armature to interrupt the first mentioned circuit, the said means likewise being adapted for closing the said second circuit, in combination with a circuit including an electro-magnet, and an armature adapted to be attracted by the first said operating coil, a circuit containing an armature adapted to be attracted by the said electro-magnet, a signal controlled by said last mentioned armature, and another normally open circuit containing an operating coil and the secondary winding of a second transformer, the said means likewise being adapted for closing the last mentioned circuit.
6. In a signaling system, a relay having a circuit, train controlled means for closing the said circuit, circuits controlled by the said relay, an audible signal and a visible signal, the closure of the latter mentioned circuits effecting the operation of the said visible and audible signal and means associated with the circuit controlled by the train controlled means for interrupting the said audible signal after a predetermined time,
7. In a signaling system for notifying the approach of a train, a normally open circuit containing an operating coil of one relay and the armature of a second, means for closing the said circuit, a second normally open circuit containing the operating coil of the said second relay, the latter mentioned coil adapted to attract the armature for interrupting the first said circuit, means for closing the said second circuit, in combination with a circuit including a pair of electro-magnets and an armature adapted to be attracted by the first said operating coil, a visual signal, a normally open circuit containing the said visual signal and a switch actuated by one of the latter mentioned electro-magnets, an audible signal, a normally open circuit containing the said audible signal, the first said switch and a second switch controlled by the other electro-magnet of said pair, mechanical means for retaining the first said switch in its actuated position to retain the visual signal actuated, and means for retaining the said second switch in its actuated position for a predetermined time to retain the said audible signal actuated for a predetermined time, and another normally open circuit containing another operating coil, and means for closing the last mentioned circuit, a third armature controlled by the last mentioned operating coil, the said mechanical means affected by the operation of the said third armature to restore the first said switch to normal, and a normally open circuit closed by the operation of the said third armature for retaining the said visual signal actuated, as long as the said third armature remains in its actuated position.
8. In a signaling system for notifying the approach of a train, a relay, an operating circuit for the said relay, train controlled means for closing the said circuit, circuits controlled by the said relay, an audible signal and a visual signal, an indication spaced from the said visual and audible signals in the direction of approach of a train for indicating to the operator of said train the fact of operation of said signals, the closure of the said circuits controlled by the said relay effecting the operation of the said visible and audible signals and said indicator, and means responsive to the closure of the said operating circuit permitting operation of the said audible signal and indicator for a predetermined time after the closure of the said circuits controlled by the said relay, and means affected by the said train for effecting a continued operation of the said visual signal and restoring the said circuits controlled by the relay to normal.
9. In a signaling system, a normally inactive relay, train controlled means for operating the said relay, a normally open circuit controlled by the said relay, an audible and visual signal, the closure of the said normally open circuit effecting the operation of the said visible and audible signal, and means responsive to the train controlled means permitting operation of the said audible signal for a predetermined time only, a normally closed circuit controlled by the said relay, a normally active marker signal, the opening of the said normally closed circuit discontinuing the operation of the said marker signal, and other train controlled means for restoring the circuits controlled by the said relay to normal.

- and effecting a continued operation of the said visual signal and retaining the said marker signal inactive.
10. In a signaling system, a signal controlling relay, vehicle controlled means for operating the said relay, a normally open signal circuit controlled by the said relay, a signal, the closure of the said circuit effecting the operation of the said signal, and means affected by the said vehicle for retaining the said relay in its operated condition to effect a continued operation of the said signal, and vehicle responsive means operable to affect the latter mentioned means to restore the said relay to normal, and other means responsive to the operation of the said vehicle responsive means for retaining the operation of the said signal after the said relay is restored to normal.
11. In a signaling system which comprises a vehicle controlled circuit, an electro-magnet controlled by said circuit, a switch controlled by said electro-magnet, a circuit controlled by the said switch which latter circuit includes a second electro-magnet, a second switch operated by the second electro-magnet, and means for retaining the said second switch in its operated position, a signal, means responsive to the operation of said second switch for displaying said signal, a second vehicle controlled circuit and an electro-magnet controlled thereby, means controlled by the latter mentioned electro-magnet for rendering the first said means ineffective to retain the said second switch in its operated position, and other means, responsive to the operation of the means controlled by the last mentioned electro-magnet for effecting a continued display of said signal.
12. A signaling system for the intersection of a highway and railroad which comprises, a switch, a pair of electro-magnets, one of said electro-magnets effecting the operation of the said switch, train controlled means for operating the said one electro-magnet to actuate the said switch, mechanical means for retaining the said switch actuated, a signal, a circuit for the signal responsive to the actuated condition of the said switch to display said signal, train controlled means for operating the said electro-magnet, and other means responsive to the operation of the last mentioned electro-magnet for effecting a continued operation of the said signal and to affect the said mechanical means for restoring the said circuit controlled by the said switch to normal.
13. In a signaling system for the intersection of a highway and a railroad, a relay, an operating circuit for the said relay, train controlled means for closing the said circuit, a normally active indication for the said highway, and a normally inactive indication for the said railroad, the said relay normally effecting the operation of the indication for the said highway, said relay operated in response to the said train-controlled means, for discontinuing the operation of the indication for the highway, and means operated in response to the said train controlled means for actuating the indication on the railroad for a predetermined time, and means affected by said train for restoring the normal condition of the said indications.
14. In a signaling system, a relay, an operating circuit therefor, means responsive to a vehicle for closing the said circuit, circuits controlled by the said relay, an audible signal and a visible signal, the closure of the latter mentioned circuits effecting the operation of the said visible and audible signal, means operable after a predetermined time to discontinue the said audible signal, and means affected by the said vehicle for effecting the continued operation of said visible signal and restoring the said circuits to normal.
15. In a signaling system, a relay, an operating circuit therefor, means responsive to a vehicle for closing the said circuit to operate the relay, circuits controlled by the said relay, a signal location marker, one of said circuits normally activated by said relay to display the said marker, a signal, another one of said circuits made active by the relay only when the said relay is operated to discontinue the said marker, and means affected by the said vehicle for retaining the said relay in its operated condition to effect a continued operation of the said signal, and vehicle responsive means operable to affect the latter mentioned means to restore the said relay to normal, and other means responsive to the operation of the said vehicle responsive means for retaining the operation of the said signal after the relay is restored to normal and for withholding operation of the said marker.

FRANK H. RICHTERKESSING.
